(57) CLAIM

The ornamental design for the purse hanger with cosmetic compact, as shown and described.

DESCRIPTION

FIG. 1 is an isometric view of the purse hanger with cosmetic compact as it would be mounted on an edge of a table showing our new design with the broken lines of the table and purse are for illustration purposes only and form no part of the claimed design;

FIG. 2 is a front elevational view thereof;

FIG. 3 is a right side elevational view thereof with the left side being identical but reversed;

FIG. 4 is a rear elevational view thereof;

FIG. 5 is a top plan view thereof; and,

FIG. 6 is a bottom plan view thereof.
